(57) **CLAIM**

The ornamental design for a notebook radiator, as shown and described.

DESCRIPTION

FIG. 1 is a first perspective view of a notebook radiator showing my new design;

FIG. 2 is a second perspective view thereof;

FIG. 3 is a third perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is a perspective view showing the notebook radiator in a use state.

1 Claim, 10 Drawing Sheets
